METHOD OF MAKING HEAT EXCHANGE APPARATUS

Edward G. Lehman, York, Pa., assignor to York Ice Machinery Corporation, York, Pa., a corporation of Delaware

Application October 12, 1938, Serial No. 234,681

3 Claims. (Cl. 113—118)

This invention relates to methods of producing finned heat exchangers of the type in which a plurality of fin plates, which may be corrugated, are threaded on a series of parallel tubes with which they are in frictional contact, though they might be sweated in place if so desired. Where frictional contact with the tubes is relied upon, it is desirable, and in fact almost necessary, to provide some means to maintain the spacing of the relatively thin fins, and one method which has heretofore been proposed is to strike up bosses or tongues from the material of the fin itself, and rely on these bosses or tongues to maintain the spacing. Where this is done some means must be provided to keep the bosses or tongues from registering with each other, as otherwise they would not serve to space the fins.

The proposal has been to adopt an asymmetrical arrangement of the bosses or fins and to reverse alternate plates end for end so that each boss or tongue of one plate came opposite a blank portion of the adjacent plate. This practice is objectionable for two reasons. It can be used only where the tubes have an absolutely symmetrical relation, for this is a necessary condition to the reversal of the position of the plates. More important still, since the fins are very closely spaced, the spacing and location of the tube openings must be absolutely precise. The precision required is greater than that attainable by commercial manufacturing methods, and even if attainable could not be maintained because of the unavoidable wear which occurs in the use of the dies. Hence, the proposal to use reversible plates while geometrically possible, is commercially unworkable, and has never attained commercial success so far as applicant is advised.

The object of the present invention is to secure the desired result without requiring reversal of the plates. With such a scheme symmetrical spacing of the tubes is not necessary and precise spacing of tube holes is not vital, because successive plates, if directly superposed, will register whether the dies are geometrically accurate or not. Whatever errors are present in one plate will be present in the next.

According to the present method, instead of forming the holes and bosses by a single dieing operation, the tube openings are produced by one operation between a pair of dies, and those tube openings are located in substantially uniform position relatively to the margins of the fin plates produced. In another dieing opera-

tion (and the two dieing operations can be carried out in any desired order) the bosses are formed. At least two types of fin plates are formed, these plates being differentiated in that the bosses or tongues are differently spaced in the two series relatively to the margins of the fin plates and consequently relatively to the tube openings. Two types of plate are enough, and it is simpler to use two than more, but the use of more than two is within the scope of the inventive concept.

Assuming that only two types of plate are used, the desired result can be secured in either of two ways. A first series of identical plates can be produced and then a second series of identical plates, the two series being differentiated as stated. Then the two types of plate are interleaved.

However, from a commercial standpoint, and for practical reasons, the simpler procedure is to feed the strip from which plates are stamped so that it passes through two dieing stations. In the first station the bosses are formed. In the second station the tube openings are formed. The dies at the two stations each have one element mounted on a single platen, and the other element mounted on a single head. The dies of one set are shiftable back and forth on the platen and head to produce the desired differentiation. The shift occurs after each dieing operation so that alternate plates belong to the two differentiated classes and will stack with the bosses or tongues of successive plates always out of register, and the tube openings always in register, if they are simply stacked as they come from the machine.

With this general statement of the principles of the invention a more elaborate description is given in the accompanying drawings, in which:

40. Figure 1 is a plan view of one type of fin plate embodying the invention;

Fig. 2 is a plan view of a second type of fin plate embodying the invention;

Fig. 3 is a longitudinal section through a partially assembled unit, showing several fin plates in stacked relation and threaded over fluid conducting tubes with which they are adapted to be employed;

Fig. 4 is an end view of an assembled unit with the tubes omitted;

Fig. 5 is a plan view of a preferred form of die head having stamping dies suitable for use in carrying out methods embodying the present invention;

55. Fig. 6 is a plan view of a sheet of fin material

showing one step of manufacture with the boss forming die of Fig. 5 in dotted line position; and

Fig. 7 is a view similar to Fig. 6, showing another step of manufacture with the boss forming die of Fig. 5 in full line position.

In the drawings, Figs. 1 and 2 illustrate the two types of fin which are preferably used in making heat exchangers according to the present invention, the fin plates being designated A and B in Figs. 1 and 2, respectively. Both of these plates are of the same outside configuration and have tube receiving openings 11 which will register when the plates are superposed. The plates are preferably corrugated as at 19. The plates contain spacing bosses 12a and 12b, the bosses 12a being in the plates A and the bosses 12b in the plates B. These bosses as shown are of concavo-convex form, but are located differently with respect to the margins of the plates and the tube openings 11 in the plates.

Reference to Fig. 3 of the drawings shows how these plates appear when they are stacked in superposed relation as they come from the punch press and are threaded over fluid conducting tubes 13. It will be apparent that all of the openings 11 are in precise register, whereas the bosses 12a and 12b are staggered with respect to one another in the successive plates. The flange portions around the tube openings 11 are adapted to contact tightly with the exterior surfaces of the tubes while the spacing bosses hold the fin plates apart as clearly indicated in Fig. 4 of the drawings.

As has been indicated above, different methods may be employed in producing fin plates according to the invention, but for purposes of illustration the preferred form only will be described briefly in connection with Figs. 5, 6 and 7 of the drawings.

Fig. 5 shows the face of the die head which carries a tube opening die 15 with punches 16 located thereon. The die head also carries a boss forming die 17 having boss forming projections 18, the die 17 being capable of reciprocating movement between the two positions, one indicated by dotted lines and the other by full lines. In the press, the die 15 will perform straight vertical movement only, into and out of contact with its associated platen, this movement of the die taking place concurrently with a similar movement of the die 17. However, mechanism is provided to shift die 17 horizontally from one of its two positions to the other between successive stamping operations. This shifting of the die 17 will, of course, be accompanied by appropriate shifting of the companion platen.

Comparison of Figs. 6 and 7 will show the steps of manufacture of the fin plates from continuous strip material by means of the dies of Fig. 5. As the material enters the press from the left as far as line X—X, we shall assume that the die 17 is in its full line position so as to produce the bosses 12a shown at the right in Fig. 6. As the material is advanced under the die 15 up to the line Y—Y of Fig. 6, the die 15 will form the openings 11 for the plate A and the die 17 the spacing bosses 12b for the plate B. Comparison of Figs. 6 and 7 will indicate that the bosses 12b are formed by the die 17 in its dotted line position, and the bosses 12a by the same die in its full line position, whereas the openings 11 formed by the die 15 will always bear the same relations to the margins of the plates.

As the material passes through the press and 75

beyond the line Y—Y in Figs. 6 and 7, it will be ready for cutting off, and the cutting operation may be carried out by a suitable cutting blade 21 carried at the outgoing end of die 15. In practice, 5 it may be also desirable to distinguish one end of a plate from another by some means such as cutting off a small corner, for example 22, on all of the plates (Figs. 1 and 2). Such a distinguishing cut is not necessary where the plates are stacked immediately as they leave the press, but it may be adopted, for example, where the sets of plates are separately formed and later interleaved. The location of the spacing bosses will serve to distinguish one type of plate from another. The dies 15 in Fig. 5 may conveniently form the corrugations 19 at the same time that the bosses and openings are produced in the plates, but the corrugating means on the die have been omitted from the drawings for the sake of clearness.

As has been pointed out above, several methods may be adopted for practicing the present invention, and all capable of producing fin plates which will always have accurately registering tube openings and non-registering spacing bosses 25 when successive plates are stacked as they leave the machine which produces them. Inasmuch as the details of machines for carrying out methods of the present invention may embody various types of construction, the basic principle of the invention in its preferred form only has been illustrated, but it is to be understood that no limitations to this particular form are intended except as such limitations may be required by the claims.

What is claimed is:

1. The method of producing a series of fin plates having registering tube openings which must align irrespective of the unavoidable inaccuracies in the construction of the punching die, 35 and spacing bosses which must not align on successive fin plates, which method consists in operating on a fin blank at two successive stations, in one of which a pair of dies produces the bosses and in the other of which another pair of dies 40 produces the openings, the two pairs of dies operating simultaneously on two successive blanks and the boss-forming die only being shifted relatively to its blank positioning means after each 45 operation, whereby the completed plates may be 50 stacked in the positions they occupy as they come from the machine with their openings in strict register and their bosses always out of register.

2. The method of producing perforated fins intended to be threaded on parallel tubes and 55 when so threaded spaced by bosses struck from the material of the fin, which method consists in feeding a strip of material from which the fins are to be formed successively between two pairs of dies, either of which pairs forms all the perforations for a fin plate, and the other of which pairs forms all the bosses for a fin plate, and 60 between successive operations of the dies shifting one pair of dies relatively to the other, whereby the bosses of successive fin plates are staggered 65 when the perforations of such fin plates are brought into alignment by superposing successive plates in the positions they occupy as they leave the second pair of dies.

3. The method of producing from a continuous 70 strip of material a series of fin plates having registering tube openings which must align irrespective of the unavoidable inaccuracies in the construction of the punching die, and spacing bosses which must not align on successive fin plates, which method consists in feeding a continuous strip of

material through a press having two stations, in one of which a pair of dies produces the bosses, and in the other of which another pair of dies produces the openings, operating said two pairs of dies simultaneously on two successive blanks, shifting the boss-forming die after each operation of the same, feeding the material forward a distance equal to the length of one pair of dies

after each operation of the dies, and cutting off the blank as each completed blank leaves the machine, whereby the completed blanks may be stacked in the positions they occupy as they leave the machine with their openings in strict register and their bosses of successive plates out of register.

EDWARD G. LEHMAN.
